UNITED STATES PATENT OFFICE.

RICHARD COLLINS, OF SPRINGFIELD, MASSACHUSETTS, ASSIGNOR TO HIMSELF AND WILLIAM C. MCCLALLAN, OF SAME PLACE.

LOOM.

SPECIFICATION forming part of Letters Patent No. 239,935, dated April 12, 1881.

Application filed June 18, 1880. (No model.)

To all whom it may concern:

Be it known that I, RICHARD COLLINS, a citizen of the United States, residing at Springfield, State of Massachusetts, have invented a new and useful Improvement in Looms, for which no patent has been obtained in any foreign country with my knowledge and consent, and of which the following is a specification.

My invention relates to the construction and 10 operation of the lathe and the let-off motion to the yarn-roll.

In the drawings, Figure I is a side elevation of so much of a loom as is necessary to show the automatic let-off motion for the warp-beam, 15 together with a stop-motion for the cloth-roll. Fig. II is a plan view of so much of a loom as is necessary to show the construction and operation of the lathe; and Figs. III, IV, V, and VI are detail views.

20 In place of the usual swinging lathe, which, if it hits the filling before or after it passes its center, strikes it at an angle to the surface of the cloth, I arrange the reed-frame F at right angles, or an approximation thereto, to the frame G, of which the lathe-beam p forms part.

The frame G is formed of the lathe-beam p and the side pieces, Q Q'. These pieces Q Q' are supported on the side frames of the loom between tracks provided with V-shaped grooves 30 and rollers similarly grooved, so that the whole frame carrying the reeds can have a horizontally-reciprocating movement imparted to it through the driving-shaft C. The shaft C has upon it the cranks e e', from which extend the 35 connections or pitmen u u' to the sides of pieces Q Q', to which they are hinged at x x'. The lathe (so called) or frame G thus receives a positive movement from the crank-shaft to cause the reed to beat the filling in the plane 40 of the cloth, while its sides and the lathe-beam are kept below or even with the top of the loom-frame, and while its slightest motions are synchronous with those of the crank-shaft all its movements are uniform. From the position of the reed F it can be securely trussed to the frame G to be prevented from springing.

To remove the possibility of springing in the beam p, I re-enforce it by a flat piece of metal, Z, arranged as shown in Fig. IV, to, in 45 effect, build up the beam of three sections, in

which the center one is the metal sheet flat in the plane of the cloth, and with its edge in the direction from which the strain upon the beam comes. In practice it is only necessary to let it into the beam for some distance to sufficiently stiffen it. When in place it is secured by screws passing through it from the beam. By this construction of beam I obviate the difficulty common to the ordinary form of lathe when the filling is driven home, the spring of 60 which, by making what is known as "rowing," causes the selvage yarn to break, and by spoiling the selvage makes cloth of an inferior quality.

The let-off motion for the yarn-roll is constructed as follows: The concave shoe 2 upon the end of bar 3 is held by weight 4 in constant contact with the warp-beam W. Its movement consequent upon any diminution of the size of the yarn-roll changes relatively 65 the position of weight 5 upon lever 6. The position of the weight upon the lever determines the amount of friction brought to bear upon a hub, 7, of the yarn-roll to cause it to revolve more easily as its circumference is reduced to maintain a uniform tension upon the warp. In detail, the rod or bar 3 is brought to the outside of the loom-frame, where it slides in bearings projecting therefrom, being kept with its shoe in contact with the yarn-roll by means of the cord e' and weight 4 secured to it passing over a pulley attached to the side of the loom-frame. From the rod 3, and secured thereto, depends the arm 8. The lower end of arm 8 is received into an offset, 9, 70 from weight 5, so that the weight can rise and fall upon the end of the arm, but be carried horizontally with the arm as it moves with rod 3. Passing through a slot in offset 9 is the lever 6, and the weight rests upon the lever, and 75 directly upon a small wheel or friction-roll, m', in the part 9, so that the weight may move is the lever as easily as possible. The lever 6 upon hinged at one end to the frame, and from a point intermediate to said hinge and the weight 80 is secured to the lever one end of a chain or cord, X, which, after being carried as many times around the pulleys or hubs a 7 as is required to produce the requisite friction, has its other end secured to the loom-frame. The 85 90 95 100

wheel L upon one end of the yarn-roll is geared to the spur A on the side of the loom-frame. I prefer a chain as a medium for conveying the friction to the hubs, as less liable to a 5 change of length through atmospheric or other causes. By this device an exceedingly sensitive automatic let-off is provided for the yarn-roll.

The automatic stopping of the cloth-roll is 10 effected as follows: Hinged at $r r$ to the frame of the loom is the rod s, which is bent at an angle on each side of its hinge, one part being carried down alongside of the loom to engage, by a hook upon its end, with the shipper 15 S resting in the angle of a projection, s' , from the lever, as shown in Fig. III, while the other part is extended to hook under the pawl T operating the cloth-roll ratchet. The movement, either automatic or manual, of the shipper S 20 to throw the belt from the pulley to stop the loom swings up the end of rod s resting upon the lever, and thereby simultaneously lifts, by means of the other hook upon rod s, the pawl T from the cloth-roll ratchet. The advantage 25 of thus stopping the cloth-roll without waiting for its stoppage in time through the stoppage of the entire loom by the snapping of the driving-belt is that a perceptible interval of time always elapses between the starting 30 of the belt by the shipper and its final transfer to the loose pulley, during which interval the belt, being operative, causes the shuttle to make one or more throws, and if the loom should have been stopped by reason of 35 the breaking of the filling it would be necessary to reverse the cloth-beam to draw the cloth,

which has meanwhile been traveling upon its roll, back to its proper position; but by the device shown the cloth-roll is instantly stopped upon any breakage of the filling.

Having described my invention, what I claim is—

1. The combination, with the side frames, J, of a loom having the V-grooved track and rollers secured to their inner sides, and the 45 driving-shaft C, provided with cranks $c c'$ and pitmen $u u'$, of the reed F and frame G, having the beam p, provided with the re-enforcing piece of metal Z, said frame being arranged to slide upon said ways and be held thereto 50 below the top of frame G with the reed vertical, and be connected at $x x$ to pitmen $u u'$, whereby the filling is beaten up and the frame sides Q Q' and lathe-beam p are kept below or even with the top of the loom-frame, as set 55 forth.

2. The combination, with the warp-beam W, of shoe 2, sliding rod 3, cord and weight $e' 4$, arm 8, weight 5, provided with offset 9 adapted to be engaged by arm 8 of rod 3, lever 6, chain 60 or cord X, and gears A L, having hubs $a 7$, whereby the shoe, following upon a decrease in size of the yarn-roll, moves the weight upon the lever to reduce the friction of the chain upon the hubs, and so automatically lessen 65 the tension upon the warp-threads, substantially as shown and described.

RICHARD COLLINS.
